Primary Examiner — Jack Reickel*Assistant Examiner* — Michael A Kervin(74) *Attorney, Agent, or Firm* — Gary Peterson(57) **CLAIM**

The ornamental design for a gate post bracket, as shown and described.

DESCRIPTION

FIG. 1 is a perspective view of a gate post bracket. FIG. 2 is a front elevation view of the bracket shown in FIG. 1.

FIG. 3 is a rear elevation view of the bracket shown in FIG. 2.

FIG. 4 is a right side elevation view of the bracket shown in FIG. 2, the left side elevation view being a mirror image thereof.

FIG. 5 is a top plan view of the bracket shown in FIG. 2; and, FIG. 6 is a bottom plan view of the bracket shown in FIG. 2.

The dashed broken line areas show portions of the bracket that form no part of the claimed design.

1 Claim, 4 Drawing Sheets(56)
